TOOL HEAD FOR INSTALLATION AND REMOVAL OF A CLEATED BOX FASTENER

Harry H. La Mar, El Segundo, and Jack H. Windle, Playa
Del Rey, Calif., assignors to North American Avia-
tion, Inc.

Application October 22, 1956, Serial No. 43,451

Term of patent 14 years

(Cl. D93—4)

FIG. 1

FIG. 2

FIG. 4

FIG. 5

FIG. 3

Fig. 1 is a front elevational view of the tool head showing our new design.

Fig. 2 is a side elevational view of the tool head shown in Fig. 1.

Fig. 3 is a reflected bottom view of the tool head design.

Fig. 4 is a top plan view of the tool head design.

Fig. 5 is a perspective view of the tool head design.

We claim:

The ornamental design for a tool head for installation and removal of a cleated box fastener, substantially as shown.
